Primary Examiner—Terry A. Wallace(74) *Attorney, Agent, or Firm*—Gordon & Jacobson, PC(57) **CLAIM**

The ornamental design for a food serving utensil, as shown and described.

DESCRIPTION

FIG. 1 is a top perspective view of a food serving utensil in a locked position;

FIG. 2 is a top view of a food serving utensil in a locked position;

FIG. 3 is a front view of a food serving utensil in a locked position;

FIG. 4 is a side view of a food serving utensil in a locked position; and

FIG. 5 is a rear view of a food serving utensil in a locked position;

FIG. 6 is a top perspective view of a food serving utensil in a closed position; and,

FIG. 7 is a perspective view of a food serving utensil in an open position.

The broken lines which define the bounds of the claimed design form no part thereof.
